UNITED STATES PATENT OFFICE.

JOSEPH F. LAMB, OF NEW BRITAIN, CONNECTICUT, ASSIGNOR TO LANDERS, FRARY & CLARK, OF NEW BRITAIN, CONNECTICUT, A CORPORATION OF CONNECTICUT.

DESIGN FOR A CASE FOR VACUUM-BOTTLES.

49,541.

Specification for Design.

Patented Aug. 22, 1916.

Application filed January 19, 1915. Serial No. 3,174. Term of patent 14 years.

To all whom it may concern:

Be it known that I, JOSEPH F. LAMB, a citizen of the United States, and a resident of New Britain, in the county of Hartford, State of Connecticut, have invented a new, original, and ornamental Design for a Case for Vacuum-Bottles, of which the following is a specification, reference being had to the accompanying drawing, forming part hereof.

The figure is a perspective view of a case

for vacuum bottles illustrating my new design.

I claim:

The ornamental design for a case for vacuum bottle, as shown.

JOSEPH F. LAMB.
